US00D989302S

(12) **United States Design Patent** (10) **Patent No.:** **US D989,302 S**
(45) **Date of Patent:** **** Jun. 13, 2023**

(54) **SYRINGE DEVICE**

- (71) Applicant: **Becton, Dickinson and Company**, Franklin Lakes, NJ (US)
- (72) Inventors: **Tianqi Hang**, Newark, NJ (US); **Elaine Tam**, Wayne, NJ (US); **Timothy Buirkle**, Parsippany-Troy Hills, NJ (US); **Amanda Masotta**, Medford, MA (US)
- (73) Assignee: **Becton, Dickinson and Company**, Franklin Lakes, NJ (US)
- (**) Term: **15 Years**
- (21) Appl. No.: **29/836,003**
- (22) Filed: **Apr. 22, 2022**

(57) **CLAIM**

We claim, the ornamental design for a syringe device, as shown and described.

DESCRIPTION

FIG. 1 is a top perspective view of a syringe device; FIG. 2 is a bottom perspective view of the syringe device of FIG. 1; FIG. 3 is a front elevational view of the syringe device of FIG. 1; FIG. 4 is a top view of the syringe device of FIG. 1; FIG. 5 is a right side elevational view of the syringe device of FIG. 1; FIG. 6 is a left side elevational view of the syringe device of FIG. 1; FIG. 7 is a rear elevational view of the syringe device of FIG. 1; FIG. 8 is a bottom plan view of the syringe device of FIG. 1; and, FIG. 9 is a side view in cross section of the syringe device of FIG. 1 taken along line 9-9 of FIG. 4.
The broken lines in the drawings illustrate portion of the syringe device and form no part of the claimed design.

1 Claim, 5 Drawing Sheets
